FURNACE

Filed July 26, 1927

UNITED STATES PATENT OFFICE

ALEXANDER MCVAY, OF SEATTLE, WASHINGTON

FURNACE

Application filed July 26, 1927. Serial No. 208,432.

This invention relates to furnaces for steam-boilers.

The object of the invention is to provide a furnace of this character which is adapted for various kinds of fuel, but more especially for burning sawmill refuse.

More specific objects and advantages of the invention will appear in the following description.

10 The invention consists in the novel construction, adaptation and combination of devices hereinafter described and claimed.

In the accompanying drawing,—

15 Figure 1 is a longitudinal vertical section of a steam-boiler furnace embodying my invention, the boiler being shown in side elevation; and Fig. 2 is a transverse section through 2—2 of Fig. 1.

20 In said drawing, the reference numeral 5 represents a steam boiler of the ordinary cylindrical type having tubes 6 for the passage of gases longitudinally from the rear combustion chamber, hereinafter referred to, of the furnace to the chimney connection 6¹ 25 at the front end of the boiler.

25 As shown in Fig. 2, the boiler is supported by bracket bars 7 upon the side walls 8 of the furnace structure. The furnace is provided with a fire box containing a primary combustion chamber 9, a second combustion chamber 10 to the rear thereof and back of which is a third combustion chamber 11.

30 The front part of the furnace structure containing said primary combustion chamber is arranged to have the latter protrude beyond the front end 6² of the boiler and the connection 6¹. Said primary combustion chamber is provided with a grate 12 which extends between the front wall 13 and a bridge wall 14 having a sloping front surface 15 which is inclined to an angle of approximately 45° from a vertical plane. Said sloping surface 15 continues to the top of the bridge wall, between which and the under- 35 side of the boiler is a restricted passage for

combustion gases between the primary combustion chamber 9 and the secondary combustion chamber 10.

40 Fuel may be supplied to the furnace through a stoking doorway 18 provided in the front wall or, preferably, through an opening 19 in the top wall 17 of the fire box as, for example, by gravitation from a fuel feeding conveyor of known construction, not shown.

45 The second combustion chamber 10 is located between said bridge wall and a baffle wall 20 positioned in proximity to the rear end of the boiler. In its lower portion, said baffle wall is provided with one or more passages 21, two being shown in Fig. 2, through which combustion gases pass from the second combustion chamber 10 into the third combustion chamber 11.

50 The baffle-wall passages 21 are, however, 65 extended forwardly as tunnels 22, into the second chamber to provide above the tunnels in the rear portion of the chamber 10 a space 60 outside of the direct path of combustion gases traveling through the second chamber 10 70 from the passage above the bridge wall to the third chamber 11.

55 The upper portion of the chamber 11 communicates with the boiler tubes 6. Primary air for combustion purposes may be supplied 75 through the ash pit 24 or directly into the fire box above the grate selectively through openings 24¹ or 18 provided in the front wall 13. Secondary air is admitted into the sec- 80 ondary chamber 10 from rearwardly directed orifices, such as 25, Fig. 1, provided in the bridge wall 14, such orifices communicating by means of a duct 26 provided in the bridge wall with a second duct 27 provided in the 85 floor below the secondary and third cum- bustion chambers and thence with a supply duct 28 provided in the rear wall 29 of the furnace, the duct 28 having near the top of wall 29 an inlet 30 for the admission of out- 90 side air. The arrangement of ducts in the

floor and walls tend to prevent the same from overheating, the heat thus taken from the structure serving to preheat the secondary air which is supplied into the furnace.

5 An opening 31 provided with a door 32 in the wall 29 permits access into the rear end of the furnace for cleaning or other purposes.

From the foregoing it will be seen that the arrangement of the furnace with the first and third combustion chambers 9 and 11 disposed in front and to the rear of the boiler exposes a maximum amount of external boiler surface to the second combustion chamber.

The fire originates in the primary combustion chamber 9 away from contact with metal heat conducting surfaces of the boiler, causing the more inflammable fuel gases to be consumed prior to contacting with the boiler. The hot burning gases produced in the fire box are directed by the sloping surface 15 of the bridge wall against the boiler and along the under surface of the latter until returned by conjoint action of the baffle wall and the draft pull, so to speak, at the entrance to the tunnel, as will be understood with reference to the direction arrows in the chamber 10 of Fig. 1. The chilling effect of the boiler contact with the burning gases reduces the temperature of the same to or below the temperature necessary for combustion. In the reverse or forward travel of the gases toward the bridge wall they encounter a fresh supply of combustion air emitted from the orifices 25 resulting in a burning of the unconsumed combustible gases in the secondary chamber which is completed in the third combustion chamber 11.

The walls of the furnace are of brick work, which become sufficiently hot to maintain combustion of fuel gases provided with a suitable quantity of air. The construction of my improved furnace and the manner of its operation will be understood from the foregoing description.

45 What I claim is:—

1. A steam-boiler furnace divided by a bridge wall and a baffle wall into three combustion chambers, with relatively small passages providing communication between the adjacent chambers above the bridge wall and through the lower portion of the baffle wall respectively, one of said chambers being located mainly in front of the boiler, the second chamber being located below the boiler and the third chamber to the rear thereof, the passages through the baffle wall comprising tunnels extending from said third chamber into proximity of the forward portion of the second chamber, and means to supply air for combustion purposes separately into both the first and second chambers.

2. A steam-boiler furnace divided by a bridge wall and a baffle wall into three combustion chambers, with relatively small passages providing communication between the

adjacent chambers above the bridge wall and through the lower portion of the baffle wall respectively, one of said chambers being located mainly in front of the boiler, the second chamber being located below the boiler and the third chamber to the rear thereof, the passages through the baffle wall comprising tunnels extending from said third chamber into proximity of the forward portion of the second chamber.

Signed at Seattle, Washington, this 29th day of June, 1927.

ALEXANDER McVAY.
